ELECTRICAL CONNECTOR OF THE
EYELET TYPEQuentin Berg, New Cumberland, Pa., assignor to
Aircraft-Marine Products, Inc., Harrisburg, Pa.

Application February 26, 1948, Serial No. 11,082

7 Claims. (Cl. 339—276)

1

This invention relates to electrical connectors, electrical connections and the method of making the same. More particularly the invention relates to connectors, connections and methods for terminating wires and like electrical conductors for facilitating their engagement and connection with screws, binding posts and other fastening means.

It has in the past been common where wires were to be connected to screws, binding posts or the like, and where space beside the connection was a problem, to form a loop in the end of a wire and to reinforce it by placing it over an eyelet and crimping the eyelet onto the loop. Such a connection is cheap, quite easy to make and requires a minimum of space beyond the binding post, etc., and therefore has been very commonly used; but it is recognized nevertheless as an unsatisfactory type of connection. The looped wire is too easily pulled out of the eyelet; the crimping of the eyelet often cuts the wire at the edge of the eyelet flange to such an extent that the wires break when subjected to vibration or flexing in service, and even when the wire is not damaged in the crimping, the sharp edge of the eyelet makes a sharply localized point of bending such that the wire may be weakened and broken by fatigue when flexed in service. There has, therefore, been a long-standing and widely recognized need for better connections. Where a ferrule extended for about half an inch, more or less, from the binding post was permissible, excellent connections have been available in recent years having pressure-formed ferrules, but these have been rejected for many important uses because of the space limitations which do not permit the projecting ferrule. For these uses the unsatisfactory eyelet has continued to be used.

The present invention now satisfies this need by using a ferrule pressure formed (or "crimped," as it is most often called in this art) onto the wire in the same manner as the proven connectors with projecting ferrules, but in this case the ferrule connection is moved so close to the opening through the tongue that the screw head or nut or other fastening would be likely to extend over the ferrule. This is made possible according to this invention by the formation of an abutment upstanding beside the hole for the screw or binding post, etc., to a height as great as that of the ferrule when crimped onto the wire. Thus the clamping pressure of the screw or the nut on the binding post or other fastening is exerted on the abutment, while the ferrule lies mostly close under the fastening with or without extending to the same height as the abutment so as to be itself directly engaged by the pressure of the fastening.

In the preferred form of the invention the contact portion of the connector is in the form of

2

a washer-like tongue with at least one edge, peripheral or central turned up to form an abutment or abutments which engages and is pressed by the fastening. If the outer or peripheral edge is turned up, it will advantageously extend from opposite sides of the ferrule around the rest of the rim of the connector; thus the ferrule itself may extend close to the hole for the fastening. When the inner or central edge is turned up there is no interference with the ferrule which may be as close as desired to the turned up central tubular abutment and the latter may therefore be completely circular. In the latter case, I have found that the axial pressure of the fastening has a tendency to compress the tubular abutment at its upper end so that it is difficult to remove from the threaded shank of the screw or binding post; but this difficulty I have overcome according to the present invention by flaring the upper end of the tubular abutment very slightly.

In the accompanying drawings I have shown several examples of the invention and I shall describe below these and various modifications and alternatives; but it is to be understood that these are not, and are not intended to be, exhaustive or limiting of the invention but on the contrary are given in order to best illustrate the invention and to instruct others skilled in this art in the principles of the invention and of its application to practical use that they may be enabled to understand it fully and to modify and adapt it to the conditions and requirements of varied uses.

35 In these drawings:

Figure 1 is a view in perspective of a strip of connectors embodying the invention which is particularly adapted for application by automatic machine;

40 Figure 2 is a plan view of the same;

Figure 3 is a view in side elevation of a connector such as one of those in the strip of Figures 1 and 2 after crimping onto a wire and mounting on a terminal screw; the wire and the conductor part engaged by the screw are broken away and the latter shown in section taken on a plane through the axis of the screw hole;

45 Figure 4 is a cross-sectional view taken on line 4—4 of Figure 3;

50 Figure 5 is a fragmentary view in cross-section taken on line 5—5 of Figure 3;

Figure 6 is a fragmentary view partly in section similar to that of Figure 3 but showing another embodiment of the invention;

55 Figure 7 is a plan view of the connector of Figure 6;

Figure 8 is a view in axial section of another embodiment of the invention; and

60 Figure 9 is a plan view of the connector shown in Figure 8.

Referring first to Figures 1 and 2, the connectors there shown are each composed of a contact tongue portion 10 and an integral ferrule-forming portion 12. The ferrule-forming portion in this case is of the type more particularly described and claimed in a copending application of James C. Macy, Serial No. 717,842, filed December 23, 1946, and as shown comprises the root area 14 with integral ears or laterally projecting portions 16 which in a suitable crimping die are curled over the root portion and back against wire 17 or other conductor placed thereon so as to make a secure low-resistance, permanent connection therewith. Although I have found great advantage in this type of connecting ferrule and crimp with the connector as shown, it is to be understood that other types of connection with the wire may be provided as desired, and in fact it is an important advantage of the present invention that it permits the designer to select the type of connection to the wire which is best for the particular application of the invention. In Figures 8 and 9 this versatility is illustrated by showing how a common type of rolled edge ferrule can be used with the present invention.

The center of the contact tongue 10 in the embodiment shown in Figures 1 to 5 is extruded into a tubular form as shown at 18, e. g. by drawing the metal of the sheet or strip, from which the connector is made, into a cup form and then punching out the bottom of the cup. In order to assure that the compression exerted by the screw 20 or nut or other fastening shall not lock the tubular abutment 18 onto the fastening 20, a punch with a 45° conical end is driven into the upper end of the abutment just enough to flare it slightly, e. g., to increase the diameter about 0.02 inch.

The height of the tubular abutment 18 is slightly greater than the ordinary height of the ferrule 12 when crimped onto a wire of the size for which it is designed. Thus the clamping pressure of the fastening 20 comes directly on the abutment 18. This relation, however, is not essential and if the abutment is slightly lower it will have the effect of exerting clamping pressure directly on the ferrule and by engaging the rim of the screw or nut at one point may help to hold it secure against loosening. The abutment 18, however, should not be so low that the screw will be bent by the unequal pressure on its head and the contact pressure thus loosened.

As shown in Figures 1 and 2 any number of these connectors may be integrally connected by leaving the ferrule-forming portion 12 of each unsevered from the tongue 10 of the next. Thus the integral series in a single strip may be as long as the sheet or strip from which it is made. Such a strip may be fed to a machine applicator wherein the last connector is severed from the strip and its ferrule crimped onto the wire.

In Figures 6 and 7 a similar connector is shown, but in this case, instead of the tubular abutment 18a being turned up from the inner or central periphery of the tongue 10a, it is in this case turned up from the outer periphery; and, since the ferrule-forming portion 12a must come close to the central opening, this means that the abutment 18a extends around less than the full circle, but advantageously is more than 180° so that it holds the screw or nut, etc., straight; or the ferrule portion may form a part of the effective abutment, being of substantially the same height as the abutment 18a when fully

crimped, so that it is directly engaged between the fastening 20 and the conducting part 22a to which the terminal is to be secured.

In Figures 8 and 9 the ferrule 12b is formed by rolling inward a lateral extension from the rim of the contact portion 10b and the abutment in this case is shown as a drawn up inner edge like that of Figures 1-5. It will be clear from which has been said above, however, that the outer edge could be drawn up in the manner shown in Figures 6 and 7. Likewise in this case or in the case illustrated by Figures 1-7 both the outer and inner edges can be drawn up to give an annular channel if desired.

This application is a continuation in part of my copending application Serial No. 773,819, filed September 13, 1947, now Patent 2,604,986, issued July 29, 1952.

I claim:

1. In a terminal binding post combination, a closed wire surrounding ferrule, a tongue contiguous with said ferrule and having a hole therein, an abutment extending upwardly from said tongue to a point at least as high as a plane tangent to the top of said ferrule, a fastening engaging in said hole having a portion thereof clamping said abutment and extending substantially over said ferrule.

2. In a terminal binding post combination as defined by claim 1 further characterized in that said abutment at least partially surrounds said hole.

3. In a terminal binding post combination as defined by claim 2 further characterized in that said abutment completely surrounds said hole.

4. In a terminal binding post combination as defined by claim 2 further characterized in that said abutment is in the form of a circumferentially interrupted cylinder, the ends thereof joining opposite sides of said ferrule.

5. In a terminal binding post combination, a closed wire surrounding ferrule, a tongue contiguous with said ferrule and having a hole therein, an abutment extending upwardly from said tongue to a point immediately above a plane tangent to the top of said ferrule, a fastening engaging in said hole having a head greater in radius than the distance from the center of the hole to said abutment and said ferrule.

6. In a terminal binding post combination, a closed wire surrounding ferrule, a tongue contiguous with said ferrule and having a hole therein, an abutment extending upwardly from said tongue to a point in a plane tangent to the top of said ferrule, a fastening engaging in said hole having a head greater in radius than the distance from the center of the hole to said abutment and said ferrule.

7. A terminal binding post combination as defined by claim 1, further characterized in that said abutment flares outwardly at its upper end to prevent locking of said fastening.
